UNITED STATES PATENT OFFICE

JOHN MARION BRASINGTON, OF CHERAW, SOUTH CAROLINA, ASSIGNOR OF ONE-HALF
TO CHARLES S. MCCALL, OF BENNETTSVILLE, SOUTH CAROLINA

FEED MECHANISM

Application filed July 3, 1930. Serial No. 465,731.

This invention relates to a feed mechanism, and it is particularly an object of the invention to provide a mechanism of this kind especially designed and adapted for use in connection with a dusting mechanism for applying powdered insecticide upon plants.

It is also an object of the invention to provide a device of this kind embodying an agitating wheel working within a hopper and which wheel is of such construction to eliminate the liability of the wheel packing the dust within the hopper, and wherein the wheel is provided with means to maintain soft unpacked dust above the discharge opening of the hopper.

A further object of the invention is to provide a mechanism of this kind including a plate adjustable with respect to the discharge opening of the hopper for regulating and controlling the discharge from said hopper and wherein is employed an agitating wheel which, during this rotation, closely approaches the discharge opening of the hopper to thereby prevent said opening from stopping up.

A still further object of the invention is to provide an apparatus of this kind wherein there is provided below the discharge from the supply hopper a container to collect dust which would otherwise probably be lost upon slowing up or stopping of the dusting apparatus.

The invention consists in the details of construction and in the combination and arrangement of the several parts of my improved feed mechanism whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawing, wherein:

Figure 1 is a view partly in section and partly in elevation illustrating a feed mecha-

nism constructed in accordance with an embodiment of my invention;

Figure 2 is a sectional view taken substantially on the line 2-2 of Figure 1;

Figure 3 is a view in top plan of the rotating plate as herein disclosed unapplied.

As disclosed in the accompanying drawing, C denotes an end portion of a cylindrical tubular casing such as is comprised in the dusting apparatus disclosed in my pending application Serial No. 399,843, filed October 15, 1929, patented August 30, 1932, No. 1,873,993, but having its outer end a closed. Disposed axially of the casing C is a shaft S driven as desired and upon which is mounted 60 for rotation therewith a cylindrical tubular member M also as disclosed in my pending application just referred to.

The casing C terminates a desired distance beyond the adjacent closed end 1 of the member M and the upper portion of the wall of this extended part of the casing is provided with an inlet opening 2. This opening 2 is defined by an upstanding flange affording a receiving spout 3 which underlies the bottom wall 4 of a supply hopper H.

The hopper H in its bottom wall 4 is provided with an opening 5 affording communication with the inlet opening 2. To one side of the opening 5 the bottom wall 4 has engaged therewith, as at 6, a rotating plate 7. This plate 7 is freely mounted on the supporting member 6 but is constantly urged toward the bottom wall 4 by a conventional expandible member 8. At predetermined points spaced circumferentially therearound the plate 7 has pressed upwardly therefrom the protuberances or parti-spherical bosses 9 provided at their axial centers with the openings 10. The openings 10 in the various protuberances or bosses 9 are of different sizes whereby means is provided to regulate or control the amount of dust discharged out the opening 5 and into the casing C through the opening 2. The opening 5, as herein disclosed, is of such size as to readily receive a protuberance or boss 9 whereby the plate 7 is readily and conveniently maintained in desired selective adjustment.

When a boss or protuberance 9 is posi-

tioned within the opening 5, the plate 7 is effectively held in desired selective adjustment and in a manner whereby is eliminated the possibility of displacement of such boss 5 or protuberance as a result of the shocks and jars incident to the use of the mechanism. This clearly avoids the disadvantage of one adjustment accidentally changing to another and thereby interfering with the desired predetermined flow and discharge of the dust.

By adjusting the plate 7, which is done manually, to bring the desired boss or protuberance 9 within an opening 5 the regulation can be obtained for the flow of the dust 15 to bring about substantially a given amount of dust per acre.

The lower portion of the hopper H rotatably supports a shaft 11 extending transversely through the hopper H and which has an extended portion in driven connection with the shaft S through a chain 12 or the like. Keyed, as at 14, or otherwise fixed to the shaft 11 at a point above the opening 5 in the bottom wall 4 of the hopper is an agitating wheel 15 having radiating therefrom a plurality of equi-distantly spaced arms 16. The outer or free extremity of each arm is beveled, as at 17, rearwardly and inwardly.

30 The diameter of the wheel 15 and the length of each of the arms 16 are such as to bring the outer end portion of each of the arms 16 in close proximity to the opening 10 in the selected protuberance or boss 9 so that the liability of stoppage of the opening 15 is substantially eliminated. This is further assured by the beveled ends 17 which provide restricted high points which quickly pass over the opening 10, thus eliminating 35 stoppage of flow out through the opening 10. These beveled ends 17 also further reduce frictional resistance to the desired rotation of the wheel.

40 Freely directed through the peripheral portion of the wheel 15 in radial alignment with an arm 16 is an annular member or ring 18 of a diameter to terminate slightly inward of the outer end of the adjacent arm 16.

45 In the present embodiment of my invention I am illustrating only one of such members or rings although it is to be understood that if desired two or more may be employed.

50 This annular member or ring 18 provides an effective means to produce soft unpacked dust directly above the discharge opening 5, or more particularly an opening 10, to facilitate the most effective discharge of dust 55 therethrough. It is also believed to be obvious that as a result of the rotation of the wheel 15 within the hopper H, the member or ring 18 prevents packing of the dust within the hopper and particularly around the 60 wheel so that the wheel rotates without re-

sistance, thus assuring a constant discharge of the dust through an opening 10.

The feed mechanism as herein disclosed is particularly intended for use in connection with a dusting apparatus, such as comprised 70 in my pending application Serial No. 399,843 hereinbefore referred to, and wherein dust as delivered within the casing C is properly drawn therefrom and discharged by suitable 75 pneumatic means.

In making a turn at the end of a row, or from other causes, the operation of this 80 pneumatic means becomes ineffective and this ordinarily would result in a considerable loss of dust or a probable piling up of 85 the dust which would interfere with the desired efficiency of the dusting apparatus.

I, therefore, find it of advantage to provide a container A of desired capacity and to place such container below an air inlet opening 19 disposed through the wall of the casing outwardly of the closed end 1 of the member M and directly below the opening 2 so that if, from any cause, the dust entering the casing C may not be properly carried 90 out by the dusting apparatus, such material will be readily received within the container A. The container A may be maintained in any desired manner in applied position and is spaced from the casing C sufficiently to 95 allow the desired ingress of air into the casing C through the opening 19. It is also to be stated that the air drawn through the casing C will serve to prevent dust escaping out through the portion of the plate 7 intersecting 100 the spout 3.

From the foregoing description it is thought to be obvious that a feed mechanism constructed in accordance with my invention is particularly well adapted for use by reason of the convenience and facility with which it may be assembled and operated, and it will also be obvious that my invention is susceptible of some change and modification without departing from the principles and 105 spirit thereof and for this reason I do not wish to be understood as limiting myself to the precise arrangement and formation of the several parts herein shown in carrying out my invention in practice except as hereinafter claimed.

I claim:

1. A feed mechanism comprising a hopper having an opening, an adjustable plate carried by the wall of the hopper, and yieldable means for constantly urging the plate toward such wall, said plate being provided therearound with a plurality of protuberances to be selectively received within the opening of the hopper, said protuberances having discharge openings, the discharge opening of one protuberance being of a size differing from that of the opening in each of the other protuberances.

2. A feed mechanism comprising a hopper 130

having a discharge opening, a wheel rotatably supported within the hopper, means for rotating the wheel, an outstanding rigid arm carried by the wheel, said arm being of a length to closely approach the opening of the hopper upon rotation of the wheel, and an annular member mounted for swinging movement on the wheel and extending beyond the periphery thereof.

10 3. A feed mechanism comprising a hopper having a discharge opening, a member rotatable within the hopper, and a member mounted for swinging movement on the rotating member and extending beyond the periphery thereof to produce soft unpacked dust directly above the discharge opening.

4. A feed mechanism comprising a hopper having a discharge opening, a wheel rotatably supported within the hopper, means for 20 rotating the wheel, an outstanding rigid arm carried by the wheel, said arm being of a length to closely approach the opening of the hopper upon rotation of the wheel, and an annular member mounted for swinging movement on the wheel at a point inwardly of and in radial alignment with the arm, the diameter of the annular member being such as to prevent the annular member swinging across the arm.

5. A feed mechanism comprising a hopper having a discharge opening, a wheel rotatably supported within the hopper, means for rotating the wheel, an outstanding rigid arm carried by the wheel, said arm being of a length to closely approach the opening of the hopper upon rotation of the wheel, and an annular member mounted for swinging movement on the wheel at a point inwardly of and in radial alignment with the arm, the diameter of the annular member being such as to allow the annular member to contact with the arm closely adjacent to the outer end thereof.

6. A feed mechanism comprising a hopper having a discharge opening, a wheel rotatably supported within the hopper, means for rotating the wheel, an outstanding rigid arm carried by the wheel, said arm being of a length to closely approach the opening of the hopper upon rotation of the wheel, and a member mounted for swinging movement on the wheel at a point inwardly of and in radial alignment with the arm, said member extending beyond the opposite sides of the wheel and having a portion contacting with the arm to prevent said member swinging past said arm.
